UNITED STATES PATENT OFFICE.

EDWARD M. JONES, OF ST. LOUIS, MISSOURI.

INCINERATOR.

Application filed August 6, 1923. Serial No. 655,938.

This invention relates to incinerators, and, more particularly to the stoker type of incinerator designed primarily for the destruction of garbage, refuse and general waste from cities, apartments, hotels, hospitals, etc., and it is a distinct and practical improvement to overcome certain practical objections to, and defects in, the general type of incinerator.

10 The objects of this invention are the provision of an incinerator, so constructed as to materially reduce the cost of incineration; first, by utilizing waste heat from combustion; second, by breaking down the moisture 15 cells in the garbage, refuse and waste materials and release the free water therein contained; also to generate and liberate, through radiation of heat into the storage bins through the arch of the upper combustion chamber and the sloping floor of storage bins, the alcoholic and ether properties from the wet materials in the storage bins; third, by preheating the air supplied to the drying hearth and burning grate to evaporate moisture from the wet materials on the drying hearth by forcing such preheated air through the mass of garbage, refuse and waste materials thereon; fourth, by supplying preheated feed air to the burning grate, such air containing the alcoholic and ether 20 fumes which together with the increased temperature of the feed air, greatly facilitate combustion; fifth, by facilitating the drying out of the wet materials on the drying hearth by deflection of heat from the baffle arch downwardly against the wet materials on the drying hearth; sixth, by completing the combustion of animal and vegetable gases resulting from combustion, in 25 their passage from the lower combustion chamber to the upper combustion chamber, the rear combustion chamber, the equalizing chambers, and the exhaust and chimney flues; seventh, by minimizing the amount of 30 labor required for operation; eighth, by gravity feed action of the garbage, refuse and waste materials, owing to the sloping floor design of the storage bins, the gravity feed charge chutes, the mechanically operated stoker valve and drying hearth members; and ninth, by minimizing the use of 35 commercial fuel, after the initial fire has been started where the garbage is of very high moisture contents and practically eliminating the use of commercial fuel after the 40 initial fire has been started where the moisture

contents of the garbage is low, through the use of the preheated air and the mechanically actuated stoker valve and drying hearth, the exposure of the wet materials to 60 the heat, the drying of the wet materials before final combustion takes place, and the supplying of preheated air carrying the alcoholic and ether vapors to the dried materials on the burning grate.

65 With the above and other objects in view, the invention consists in the novel features of construction, arrangement and combination of parts hereinafter more fully described and finally pointed out in the claims 70 hereto appended.

75 Referring to the accompanying drawings forming a part of this specification, wherein like characters of reference denote similar parts throughout the several views:

Fig. 1, is a side elevation of the incinerator with portions thereof broken away.

Fig. 2, is a horizontal transverse sectional view taken on line 2—2 of Figs. 1 and 4.

Fig. 3, is a transverse vertical sectional view taken on line 3—3 of Fig. 2 of an incinerator embodying the features of this invention.

Fig. 4, is a longitudinal vertical sectional view of the incinerator, taken on line 4—4 of Fig. 2.

Fig. 5, is a transverse horizontal sectional view of the incinerator, taken on line 5—5 of Fig. 4.

Fig. 6, is a transverse horizontal sectional view of the incinerator, taken on line 6—6 of Fig. 4.

Fig. 7, is a transverse horizontal sectional view of the incinerator taken on line 7—7 of Fig. 4.

Fig. 8, is a reduced transverse horizontal sectional view, taken on line 8—8 of Fig. 4 and including the stack foundation.

Fig. 9, is a detail in perspective of one of the stoker drying hearth members.

Fig. 10, is a view in detail showing one of the storage bins, gravity chute, stoker grates, burning grate, combustion chamber, outlet to heater chamber and the baffle arch and the mechanism for actuating the stoker drying hearth.

In carrying out the aim of this invention, I employ a suitable housing structure represented by the reference character 1. Within the forward upper portion of the housing structure, I provide one or more opposed receiving and storage compartments, chambers

or bins 2 for receiving garbage and refuse as delivered to the incinerator bins through the openings 3 by collection vehicles, or otherwise. The storage bins 2 are separated by means of a suitable partition 4 and each bin 2 is provided with a downwardly and outwardly inclined or sloping floor 5 which terminate at their outer edge in a downwardly directed wall portion 6 to provide a gravity feed passage or chute 7 for each bin 2 within the side wall of the housing structure 1. Each feed passage or chute 7 is provided with an inclined floor 8 for directing garbage and refuse toward and against a suitable stoker valve 9 which is preferably provided with a plurality of draft openings 10 arranged at the discharge end of the gravity feed passage, and at the upper end of an inclined stoker drying hearth, which hearth consists of a plurality of pivotally supported stoker drying hearth members 11 which are preferably provided with a plurality of draft openings 12. The hearth members 11 are actuated in unison and opposite to the valve 9 by means of the levers 13 connected at their upper ends to the hearth members and at their opposite ends to a connecting bar 14 which bar 14, in turn, is operatively connected to the upper end of a crank arm 15, which arm is pivotally connected at its lower end to a suitable crank disk 16 mounted upon a shaft 17 and driven by means of a worm gear 18, which gear is also fixed to the shaft 17 and is driven by means of a worm 19 fixed to a driven shaft 20. The shaft 20 is preferably driven through the medium of an electric motor 21 and a train of suitable gearing 22. The disk 16 also actuates the stoker valve 9 through the medium of the lever 23 and a crank connecting rod 24. By this arrangement, it is evident that in the action of the stoker drying hearth, the stoker valve 9 is depressed or lowered in an arcuate path as the stoker drying hearth members 11 are raised in an arcuate path, and vice-versa. As the drying hearth members 11 are raised and stoker valve 9 is lowered, garbage, refuse and waste materials pass from the gravity chute and pass against the drying hearth members 11 and as the drying hearth members 11 are depressed or lowered, the stoker valve 9 is raised thereby checking further passage of garbage onto the drying hearth members 11 until the next revolution of the crank disk 16. Briefly, the garbage is intermittently moved along the drying hearth members 11 and is only moved at each revolution of the disk 16 a distance equal to the width of one of the drying hearth members 11.

From the drying hearth members 11, the garbage is deposited into a suitable fire box or burning grate 25 which is preferably provided with a plurality of draft openings 26. The burning grate is situated intermediate

the inner end of the stoker drying hearths, as clearly shown in Figs. 3 and 6.

A suitable baffle arch 27 is arranged above the burning grate 25 and the stoker drying hearths. The arch 27 is provided to form a lower combustion chamber 28 between the arch 27 and the grate 25 and stoker drying hearths.

29 represents a suitable arch provided with an upper facing of suitable insulating material 30 which arch forms an upper combustion chamber 31 between the baffle arch 27 and the arch 29. The lower and upper combustion chambers 28 and 31 communicate with each other to either side of the baffle arch 27 through the medium of suitable passages 32 which are situated above the upper ends of stoker drying hearths, as clearly shown in Figs. 3 and 10.

The rear wall 33 of the upper combustion chamber 31 is provided with a suitable checker screen flue 34 which communicates with the upper end of a rear combustion chamber 35 which chamber has a dust pit 36. This chamber is directly back of chambers 28 and 31 and extends from the floor 37 of the incinerating housing to an elevation equivalent to the arch 29, as clearly shown in Fig. 4.

The rear combustion chamber 35 communicates at its lower end through the medium of a series of flues 38 in the wall 39 with a lower equalizing chamber 40 having a dust pit 41. 42 represents an upper equalizing chamber situated directly above the lower equalizing chamber 40 and is provided with a series of removable cover plates 43. A suitable preheater device consisting of a plurality of suitably spaced tubes 44 is arranged intermediate the lower and upper equalizing chambers 40 and 42 so that the gases may pass from the lower equalizing chamber 40 to the upper equalizing chamber 42 through the tubes 44. The passages between the spaced tubes 44 provide a passage or chamber 45 which is separated from the lower and upper equalizing chambers 40 and 42 by means of the walls 46 and 47, respectively. This arrangement may be reversed, if desired, so that the gases will pass around the tubes instead of through them by laying them horizontally, thus causing the exhaust gas to pass around the tubes to the exhaust flue.

48 indicates an exhaust flue having suitable communication at its inner end with the upper equalizing chamber 42 through the flue openings 49, and at its outer end with a suitable stack 50 provided with a dust pit 51 at its lower end.

52 indicates a cold air duct which communicates with the screened openings 53. These openings 53 are formed in the rear walls of the garbage storage bins 2 and lead from the storage bins to the duct 52, as

clearly shown in Figs. 3 and 4. The cold air duct 52 leads to a suitable cold air blower 54 which is driven by means of a suitable electric motor 55.

5 Leading from the blower 54 is an underground cold air duct 56 which in turn communicates with a hot air duct 57 through the medium of the passages 45 surrounding the preheater tubes 44 between the lower 10 and upper equalizing chambers 40 and 42. The hot air duct 57 is directed underground to a point below the burning grate where it communicates through the medium of a valved duct 58 with an air chamber 59 leading 15 to the burning grate. Arranged upon opposite sides of the air chamber 59 to the burning grate, are suitable hot air chambers 60 which are positioned below the drying hearths and which communicate with 20 the lower combustion chamber 28 through the spaces 61 between the hearth members 11 and the openings 12 therein. The hot air duct 57 is provided with a pair of branch ducts 62 which supply hot air to the air chamber 60 below the drying hearths.

25 A by-pass duct 63 has communication with the cold air duct 52 and is provided with a balanced valve 64 to be opened when the blower is not running.

30 The upper floor of the incinerator housing structure 1 is provided with a perforated member 65 as a closure for each garbage receiving opening 3 and to permit the passage of cold air into the storage bins. The upper floor is also provided with inspection openings 66 which are closed by means of the removable cover plates 67.

35 Air chambers 59 and 60 are each provided with a clean out opening 68 in the front wall thereof and they are closed by means of a suitable removable closure 69.

40 The rear combustion chamber 35 and the lower equalizing chamber 40 are each provided with clean out openings 70 provided with the removable closures 71.

45 The stack is also provided with a clean out opening 72 which is provided with a removable closure 73.

50 The operation of the device is as follows:

55 In the initial starting of the incinerator, a suitable fuel is set on fire upon the burning grate and the blower is started. The garbage, refuse and foreign waste materials are dumped into the storage bins 2 through the openings 3 from the collection vehicles. The garbage is fed by gravity over the sloping floor of bins 2 to the gravity chutes 7 and rests on the sloping floor 8 thereof and against the valve 9 which is up. Owing to the fact that the sloping floors of the storage bins are directly above the lower and upper combustion chambers, heat is transmitted to them and the moisture cells of the garbage stored in the bins are initially broken down, permitting the freed water

therefrom to pass down the sloping floors of the bins into the gravity feed chutes and into the lower combustion chamber. The freeing of this water also permits the garbage to easily slide downwardly toward the 70 gravity chutes. The heat applied to the garbage and refuse in the storage bins through the floor of the bins, brings about a fermentation process, develops and releases 75 alcoholic and ether gases contained in the garbage and refuse. All of these gases have a combustion value which, when drawn from the storage bins, passed through the preheater and are fed to the drying garbage upon the stoker drying hearth and to the 80 burning garbage in the burning grate, facilitate combustion.

85 As the garbage and refuse moves into and through the gravity feed chutes to the stoker drying hearths, it is held in check by the stoker valve 9 until the crank actuating mechanism lowers the stoker valve and raises the drying hearth members, intermittently, thus advancing turning over and over the garbage and refuse fed over the 90 garbage drying hearth by the action of the valve 9 and hearth members 11. The intermittent turning over of the garbage upon the drying hearth members permits the preheated air and gases to pass upwardly 95 through the garbage and refuse mass upon the stoker hearths from the hot air delivering ducts, thereby exposing all parts of the mass to the preheated air and reflected heat and flames of the lower combustion chamber thereby bringing about a rapid drying out 100 process of moisture within the mass and with certain kinds of garbages burning same by the time the drying garbage mass has advanced along the entire length of the drying hearth and dumped into the burning grate where the burning thereof is completed.

105 As the burning of the dried garbage mass takes place upon the burning grate the hot flames and gases from the burning mass are deflected by the arched baffle downwardly against the garbage being turned over and advanced intermittently by the stoker drying hearth, thence through the arch openings leading from the lower combustion chamber to the upper combustion chamber. From the upper combustion chamber the hot gases and flames are drawn through the checker screen flues into the rear combustion chamber from where they pass downwardly and through the plurality of flues leading into the lower equalizing chamber. From here the gases pass upwardly through the preheating tubes into the upper equalizing chamber, thence into the chimney or stack flue through the connecting flues.

110 Owing to the fact that the preheater tubes are arranged in staggered relation, they offer the greatest amount of exposure to the 115 120 125 130

contaminated cold air being driven between them by the blower. The cold air supplied to the preheater is first drawn through the perforated closures of the garbage receiving opening into the storage bins where its absorbs the odors, alcoholic and ether gases from the garbage therein and then from the storage bins through the screened openings into the cold air duct to the blower from where it is driven through the passages of the preheater. The temperature of the air from the blower is raised several hundred degrees in its passage between the preheater tubes and then this preheated air is finally passed through hot air delivery ducts to the hot air chambers below the burning grate and stoker garbage drying hearth. This forced hot air speeds up drying process of moisture in the garbage and refuse mass and materially facilitates combustion in the burning grate.

The progressive and continual turning over of the wet garbage and refuse mass upon the drying hearths, and the subsequent exposure to the heat of the lower combustion chamber, coupled with the forced preheated air passing through the mass from the hot air chambers below, dries the garbage mass to a combustible state by the time it has advanced from the stoker valve upon the drying hearth members to the burning grate. The dried garbage and refuse mass burns readily itself, but the preheated forced air draft supplied, hastens and facilitates combustion there also and permits the operation to proceed without further attention as to the supplying of fuel to burning grate after its initial charge.

The many advantages of the herein described invention will readily suggest themselves to those skilled in the art to which it appertains.

I do not desire to be understood as limiting myself to the exact details of construction and arrangement of parts as herein described and illustrated, as it is manifest that variations and modifications may be made without departing from the spirit and scope of my invention and the terms of the following claims, hence I wish it to be understood that I reserve the right to make any such changes, or modifications as may fairly fall within the scope of the appended claims when fairly construed.

What I claim is:

1. In an incinerator structure of the class described, a floor, oscillating drying hearths, an arched structure having a series of flame and smoke openings, said floor, drying hearth and arched structure forming, in conjunction with the walls of the incinerator, a pair of storage bins, a lower combustion chamber, an upper combustion chamber, a rear combustion chamber, a lower equalizing chamber, an upper equalizing chamber, a

preheater disposed between said equalizing chambers forming a heating chamber, a forced draft mechanism, an air and gas conduit leading from the storage bins to said forced draft mechanism, a conduit leading from the forced draft mechanism to and through the heating chamber, a fuel burning grate, a forced preheated air and gas chamber formed under the fuel burning grate and each oscillating drying hearth, a branched forced hot air and gas conduit leading from the heating chamber to said forced preheated air and gas chamber, means for permitting the passage of forced hot air and gases from said preheated air and gas chamber through the burning grate and oscillating drying hearths upwardly into the lower combustion chamber and smoke outlet means connecting with the upper equalizing chamber.

2. In an incinerator structure, inclined oscillating garbage drying hearths, a burning grate disposed between the hearths, a floor having perforated charge openings, an arched structure having a series of flame and smoke flues, said hearth, burning grate, floor and arch structure forming in conjunction with the walls of the incinerator, a garbage storage space, hot air chambers disposed below the fuel burning grate and the drying hearths, a preheater, means for conducting air and gases from the garbage storage bins to and through the preheater for heating the air and gases and delivering same to the hot air chambers for forced delivery upwardly through the oscillating hearths and garbage mass thereon and the burning grate and the burning garbage therein, a lower combustion chamber having passages communicating with said storage space, an upper combustion chamber having communication at its sides with the lower combustion chamber, flame and heat deflecting means arranged in the lower combustion chamber, a rear combustion chamber, means for dividing and equalizing the flames and smoke as they pass from the upper combustion chamber into the rear combustion chamber, lower and upper equalizing chambers for said preheater and outlet flues communicating with the upper equalizing chamber.

3. In an incinerator structure, a housing, a garbage storage bin having an inclined floor, an inclined oscillating garbage drying hearth, a burning grate disposed at the lower end of said hearth, a preheater, an arched structure having one of its end walls provided with a plurality of flame and smoke flues, said housing, hearth and arched structure forming, in conjunction with the walls of the housing, a lower combustion chamber, an upper combustion chamber, a rear combustion chamber, an equalizing chamber disposed at opposite ends of said preheater, a

hot air chamber disposed below said hearth and a hot air chamber below said burning grate; a forced draft mechanism, an air and gas conduit leading from the storage bin to said forced draft mechanism, a forced hot air conduit leading from the preheater to the hot air chambers under the drying hearth and burning grate and a stack having communication with one of the equalizing chambers.

4. In an incinerator construction, a housing structure provided with a storage bin having a sloping floor, means of admitting air into the bin, an inclined stoker drying hearth, a gravity discharge chute between the drying hearth and the storage bin, a valve for controlling the feed of garbage to the drying hearth intermittently, a burning grate at the lower end of the drying hearth, a baffle arch disposed between the sloping floor of the bin and burning grate, a lower combustion chamber formed below the baffle arch, an upper combustion chamber formed above the baffle arch, a passage connecting said combustion chambers, a rear combustion chamber, a series of flues connecting the

upper end of the rear combustion chamber with the upper combustion chamber, a lower equalizing chamber, an upper equalizing chamber, preheater tubes disposed in spaced relation between the upper and lower equalizing chambers permitting of communication therebetween, an exhaust flue communication with the upper equalizing chamber, a stack flue communication with said exhaust flue, a cold air duct leading from the storage bin, a blower connected to the cold air duct, means for driving said blower, a preheating chamber surrounding the preheater tubes, a forced air duct leading from the blower, a hot air chamber below the drying hearth, a hot air chamber formed below the burning grate and the drying hearth, a valve controlled hot air delivery duct connecting the preheating chamber with the aforesaid hot air chambers, a duct leading from the cold air duct to one of the equalizing chambers and a counterbalanced valve for said duct.

In testimony whereof, I have hereunto signed my name to the specification.

EDWARD M. JONES.
